UNITED STATES PATENT OFFICE.

ALONZO M. MACE, OF NEEDHAM, MASSACHUSETTS.

IMPROVEMENT IN LAMPS.

Specification forming part of Letters Patent No. 129,973, dated July 30, 1872.

SPECIFICATION.

I, ALONZO M. MACE, of Needham, in the county of Norfolk and State of Massachusetts, have invented certain Improvements in Kerosene and other Carbonaceous Oil Lamps, of which the following is a specification:

Figure 1 of the accompanying drawing represents a central vertical section of my improved lamp.

The present invention relates to certain new and useful improvements in lamps for burning kerosene and other carbonaceous oils, or their equivalents, whereby the use of chimneys is dispensed with and a steady and brilliant flame, without disagreeable odor, is produced, and the liability of accident from the overheating of the reservoir-cap is prevented.

My improvements consist, mainly, in so arranging an air-chamber in connection with double-wick tubes of a kerosene or other equivalent oil lamp as to cause the cool air to enter the bottom of said chamber and pass up and circulate around the said wick-tubes, thereby preventing them from absorbing too much heat from the flame, and so cooling the cap of the lamp-reservoir as to avoid the possibility of danger from its overheating; also, of so arranging a supplementary cap in connection with the air-chamber and a perforated or other holder or frame as to force the heated air ascending around the upper portion of the wick-tubes to pass between the top of the wick-tubes, thereby supplying the flame with the hot oxygen necessary to make good combustion, and so that the heat absorbed by the cap from the wick-tubes shall be conveyed to it and be taken up by the air passing through or in contact with it, and conveyed to the secondary or ordinary burners, thereby supplying them with hot oxygen and insuring an even, brilliant flame, free from disagreeable odor or smoke, &c.

In the drawing, A represents the body or reservoir of a lamp, provided with a cap, b, in which screws the bottom of a screw-base, d, in which turn two parallel arbors carrying two pairs of ratchet-wheels, one pair, e e', shown in the drawing, the ratchets of each arbor engaging with those of the opposite arbor and with wicks f f' that are operated up and down

in vertical parallel tubes, g g', extending up from the top of the base d, and sloping toward each other at the top. Attached to or formed on a perforated dome or other suitable-shaped cap or frame, h, and extending over the wick-tubes g g', and, if desired, over the base d, at a proper distance, is a conical or other suitable-shaped tube, k, which forms a space or air-chamber, p, between it and the outside of the wick-tubes g g'. Attached to or formed in one piece with the top of the perforated cap or frame h is a cap, l, its sides extending upward and diminishing at the top, which is of a sufficient distance below the top of the wick-tubes g g' to prevent any smoke from the flame or charring of the wick. Resting upon or supported by the cap or frame h is a secondary burner, m, arranged, as ordinarily, with an inner burner, n, slots m' n', and air-space o.

The operation of my invention is as follows: Light being applied to the wicks f f', which pass up from the reservoir a through the tubes g g', which are arranged, as shown, parallel to each other, and with a passage between and around them for the circulation of air, which, by the heat communicated to the wicks f f', is carried up from below the bottom of the air-chamber p around the wick-tubes g g', thus preventing them from absorbing too much heat, and directing the cool air against the cap b of the lamp-body a, thereby obviating the possibility of any accident from the explosion of gas in the top of the reservoir or body a by the overheating of the cap b, the air, passing up the air-chamber b, becomes heated as it reaches the top, where, by means of the sloping cap l, it is carried around and between the top of the wick-tubes g g', thereby supplying the flame with hot oxygen and perfecting the combustion. By means of the cap l, connecting with the perforated or other cap or frame h, and which may be formed as a continuation of the tube k, if desired, the heat absorbed from the wick-tubes g g' by the cap l is conveyed to the cap or frame h, and taken up by the air passing through or in contact with it, and conveyed through the secondary burners m and n, thereby supplying them with hot oxygen, and producing a clear, steady

light, free from disagreeable odor, and thereby obviating the use of chimneys.

Having thus described my improvements, what I claim as my invention, and desire to have secured to me by Letters Patent, is—

The combination of the double-wick tubes *g g'*, set at such an angle as to produce a compound flame, with the air-chamber *p*, the cap *l*, the perforated or equivalent cap or frame *h*,

and burners *m n*, arranged in an "in-chimney lamp," substantially as set forth.

In testimony whereof I have signed my name to this specification in the presence of two subscribing witnesses.

ALONZO M. MACE.
